UNITED STATES PATENT OFFICE.

THEODORE MILLER, OF DETROIT, MICHIGAN, ASSIGNOR TO THE ART STOVE COMPANY, OF SAME PLACE.

DESIGN FOR AN OIL-STOVE.

SPECIFICATION forming part of Design No. 24,286, dated May 7, 1895.

Application filed January 17, 1895. Serial No. 535,276. Term of patent 7 years.

To all whom it may concern:

Be it known that I, THEODORE MILLER, a citizen of the United States, residing at Detroit, in the county of Wayne, State of Michigan, have invented and produced a new and original Design for Oil-Stoves, of which the following is a description, reference being had to the accompanying drawings, showing a part thereof.

10 In the drawings, Figure 1 is a view in perspective illustrating my invention. Fig. 2 is a view showing the design in end elevation.

The leading features of my design consist of the frame the two ends of which, A, A', are 15 each formed of upwardly extended ornamental curved front and rear bars a a' , connected toward their lower ends with a plain cross bar a^2 and intermediate their ends with a curved cross bar a^3 ornamented with scroll work.

20 Toward the upper ends the front and rear bars are connected with ornamental curved bars A^2 bifurcated at the front and rear thereof and ornamented intermediate the ends with scroll work as at a^4 . The end portions A, A' 25 of the frame are connected at the rear of the stove with an ornamentally curved bar B. Upon the upper ends of the two ends A, A' of the frame, is a plain top C bearing intermediate its front edge an ornamental panel C'.

A chamber D, elliptical in cross section, and 30 beaded on the exterior, as shown at d , rests at its extremities upon the ornamental cross bars a^3 . Toward the lower ends of the bars A, A', is a plain shelf E above which, and in front of said chamber, appear cylindrical chambers F 35 beaded on their exterior, as shown at e , their lower ends extending downward in contact with and resting upon said shelf, said chambers F being of larger diameter toward their upper ends and surmounted by cylindrical 40 chambers F^2 , F^3 provided with light openings F^4 and beaded on either side of the light openings as shown at f . The light openings are surrounded by frames essentially rectangular in form, the corners of said frames being 45 slightly rounded. A frame of this design permits the chamber D together with the chambers F and chambers F^2 F^3 to be lifted and removed from the frame.

What I claim as my invention is— 50

The design for an oil stove, substantially as shown and described.

In testimony whereof I have signed this specification in the presence of two witnesses.

THEODORE MILLER.
